The ornamental design for a gateway terminal, as shown and described.

DESCRIPTION

FIG. 1 is a top, front, left perspective view of a gateway terminal showing my new design;

FIG. 2 is a top, rear, left perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an exploded top, front, left, perspective view thereof.

The broken lines in the drawings show portions of the gateway terminal that form no part of the claimed design. The broken line bracket shown in FIG. 9 view indicates the association of elements of the exploded view; the broken line bracket forms no part of the claimed design.
